UNITED STATES PATENT OFFICE.

THOMAS FITCH ROWLAND, JR., OF BROOKLYN, NEW YORK, ASSIGNOR
TO THOMAS F. ROWLAND, SR., OF BOROUGH OF MANHATTAN, NEW
YORK, N. Y.

CIRCULAR-FLANGING MACHINE.

SPECIFICATION forming part of Letters Patent No. 681,512, dated August 27, 1901.

Application filed January 23, 1901. Serial No. 44,383. (No model.)

To all whom it may concern:

Be it known that I, THOMAS FITCH ROWLAND, Jr., a citizen of the United States, residing at the borough of Brooklyn, city of New York, in the county of Kings and State of New York, have invented a new and useful Circular-Flanging Machine, of which the following is a specification.

My invention relates to mechanism by which metal plates of considerable thickness may be flanged circularly; and the objects of my invention are to provide a machine by which such circular flanging can be efficiently performed and to arrange the parts of the machine so that circular flanges having different radii may be made by the same machine.

In general the features of my invention consist of a properly-shaped flanging hammer and anvil preferably carried on the same base and the hammer being operated by any suitable power, a blank-carrying table upon which the plate to be flanged is carried into position between the hammer and anvil, the said table being pivoted and being capable of a circular movement in a horizontal plane, and an arrangement of parts whereby the position of the pivot upon which the blank-carrying table turns may be changed relative to the anvil, thus changing the radius of the arc described by the outer end of the blank-carrying table.

In the accompanying drawings, which form part of this specification, I have illustrated what now seems to me the best embodiment of my invention.

Figure 1 is a plan view of my machine from above. Fig. 2 is a vertical longitudinal section, the hammer and anvil being shown in side elevation; and Fig. 3 is a rear end view of the mechanism.

Similar letters refer to similar parts throughout the several views.

A represents the blank-carrying table, which is pivoted on the vertical shaft C and the outer periphery of which is preferably curved. The outer end of the blank-carrying table is supported on swiveled rollers *a a*, which travel over a bed-plate B, which is here shown as having a crescent-like shape and as supported on I-beams B' B'. Just beyond

the outer end of the central portion of the table A and preferably on a level with its upper surface is located the anvil S, in conjunction with which is operated a hammer R, which may be driven by any suitable power 55 and is here shown as operated by a hydraulic cylinder R'. Preferably the anvil S and the hammer R are carried by the same base, here shown as T, but which may be of any other suitable shape. I prefer that the anvil 60 S should not be integral with the base T, but should be separable therefrom and be seated therein in any suitable manner. Thus anvils of different shape may be substituted as may be desirable in making circular flanges of 65 different radii. It is also desirable to carry the inner portion of the base T upward close to the bottom of the outer portion of the table and in such portion of the base T to locate a roller W, the axis of which lies in the line 70 drawn from the center of the anvil to the center of the pivot C. The diameter of this roller is such that the outer end of the table A rests lightly upon its periphery and is partially supported thereby when the blank is 75 on the table. I provide this table and the shaft C, to which it is centrally pivoted, with suitable mechanism, to be hereinafter described, for giving the outer end of the table a circular movement. Thus different portions of the plate or blank carried by the table are successively brought between the hammer and the anvil and are acted upon, thereby forming a circular flange. It will be apparent, however, that other means and mech- 80 anism than that which I have illustrated and described herein may be used for causing the circular movement of the table. I also provide means, to be hereinafter described, whereby the shaft to which the blank-carry- 85 ing table is pivoted and through which the circular movement is imparted to the table may be moved nearer to or farther from the anvil without altering the position of the table, thus shortening or lengthening the radius of 90 the arc described by the periphery of the table. A slot A' extends part of the way along the longitudinal axis of the table A, through which slot projects the top of the pivot-shaft C. A reinforcing-plate, as A², 95 100

may, if desired, be attached to those parts of the table A contiguous to the slot A'. The shaft C is carried by and free to rotate in a bearing or carriage D, which is supported 5 and slides upon the top of suitable tracks, as E E. The carriage D consists of an upright sleeve or bearing, with a horizontally-extending platform D' D', which platform rests and slides upon the top of the tracks E E. The 10 outer edge of this platform is preferably flanged, as at D⁴, to strengthen the platform. Seated upon the lower part of the carriage D is a second vertical sleeve D², which is free to rotate on its bearing. This sleeve is keyed 15 to or otherwise connected with the shaft C. The platform D' carries the bearings D⁵ D⁵ for the shaft G⁵. The entire carriage D and its several parts are capable of motion toward and away from the anvil S. The pivot-shaft 20 C extends through the slot A' and through the vertical sleeves of the carriage D. Forged to or otherwise rigidly connected with the upper portion of the shaft C is a rectangular head C', which fits the slot A' and is free to 25 be moved back and forth along said slot, but cannot be turned therein. To the portion C⁴ of the shaft C just below the head C' is keyed or otherwise rigidly connected the sleeve D². Preferably the lower part of the portion C⁴ of 30 the shaft is threaded and fits into similar threads on the inner periphery of the lower portion of the sleeve D². A washer and nut C⁶ are attached to the lower end of the shaft C to prevent the shaft rising in its bearings. 35 A plate C⁵ is bolted to the lower portion of the carriage D, said plate extending under the tracks E E, thus preventing the rising of the entire carriage D. On the upper end of the shaft C where the same projects above 40 the table A is fitted a large washer C² and a nut C³. When the nut C³ and washer C² are loosened, the entire carriage D and the pivot-shaft C may by the suitable application of force be moved along the slot A' toward or 45 away from the anvil S.

In the drawings I have shown the following means for moving the carriage and shaft: F is a threaded shaft carried in the bearing F², which is attached to the tracks E E. On 50 the outer end of this shaft is a hand-wheel F', and on the inner end is a head F³, which head engages with the rear portion of the carriage D. The head F is contained in a box F⁴. By turning the hand-wheel to the right or 55 left the carriage D is pushed toward the anvil S or pulled away from it, respectively. In this way the distance from the anvil S to the pivotal point upon which the table A turns may be lessened or increased and the radius of the 60 circular flange made by the machine may be correspondingly changed. When the carriage D and the pivot-shaft C have been moved to the desired point in the slot A', the nut C³ and the washer C² are tightened, thus clamping 65 the sleeve D², the head C', and the table A tightly together and preventing any movement of the shaft along the slot. Power is

then applied to rotate the shaft, and this motion is imparted through the head C' to the table A and to the blank carried by the table. 70

In the drawings I have shown the following means for imparting circular motion to the blank-carrying table A:

G is a motor of any suitable kind, which operates the gear-wheels G' and G². This rotation is transmitted through the worm G³ and the worm-wheel G⁴ to the shaft G⁵, one end of which is supported in the bearings G⁶, attached to the track E, and other portions of which are supported in the bearings D⁵ D⁵, 80 connected with the carriage D. The shaft G⁵ is grooved along its length, as shown at G⁷. The worm L, having an interior feather, which projects into the groove G⁷, is fitted upon the shaft G⁵, said worm being capable of longitudinal movement along the shaft G⁵ and being held in the bearings D⁵ D⁵, and thus compelled to take on such horizontal movement along the line of the shaft G⁵ as may be imparted to the carriage D. Projecting from 90 the sleeve D², which surrounds and is rigidly connected with the pivot-shaft C, is a quadrant M, having an exterior part m, which meshes with the worm L. When the motor G is set into operation, its power is transmitted to the shaft G⁵ and thence through the worm-wheel L to the quadrant M. As the quadrant travels in its circular path that motion is imparted through the head C' of the shaft C to the table A and to the blank or 95 plate carried by the table. 100

In the present instance I have shown upon the table a cylindrical blank X, having a projecting rim x, which it is desired to flange circularly.

x' represents the position of the rim after it has been subjected to the flanging action of the hammer R.

a' illustrates a suitable clip for holding the cylindrical blank in position upon the table 110 while it is being subjected to the flanging action.

If the outer edge of the table A be made circular, its contour should correspond with the arc of a circle having a radius equal to the 115 distance from the edge of the table to the pivot when the shaft C is at its nearest point to the anvil. When the pivot-shaft is in that position, not only will the middle point of the outer edge of the table be close to the anvil, 120 but every other point on the edge of the table will in turn pass the anvil at the same distance. When the pivot-shaft is moved farther away from the anvil, although the middle point of the outer edge of the table 125 will always pass the anvil at the same distance, points lying toward the sides of the table will pass the anvil at varying distances. The blank, however, projects from the table sufficiently to be brought between the hammer and the anvil along the entire line of the 130 proposed circular flange. In referring to the edge of the table being contiguous to the anvil I do not mean, therefore, that every point

- on the edge of the table is, as the table rotates, brought equally near the anvil, but simply that the anvil is located in a general sense near or contiguous to the outer edge of the
- 5 pivoted table, which may be of any desired shape and at varying distances from the anvil, the only essential feature being that it should be near enough to carry the blank between the hammer and anvil.
- 10 The tracks E E, the I-beams B' B', and the base T are supported by the cross I-beams B² B² or on any other suitable base.
- Having described my invention, what I claim as new, and desire to secure by Letters 15 Patent, is—
1. In a machine for circularly flanging plate metal, the combination of an anvil, a pivoted blank-carrying table, the periphery of which is contiguous said anvil, means for imparting 20 to said table a rotary horizontal movement about the said pivot, and a flanging-hammer coacting with said anvil, whereby protruding portions of a blank of plate metal may be successively flanged between said hammer and
- 25 anvil along the arc of a circle.
2. In a machine for circularly flanging plate metal, the combination of an anvil, a pivoted blank-carrying table, the periphery of which is contiguous said anvil, said table having a 30 central longitudinal slot through which the pivot projects, means for moving said pivot along said slot either nearer or farther from the anvil, means for imparting to said table a rotary horizontal movement about said
- 35 pivot, and a flanging-hammer coacting with said anvil, whereby by adjustment of said pivot in said slot circular flanges having different radii may be made.
3. In a machine for circularly flanging plate 40 metal, the combination of an anvil, a pivoted blank-carrying table the periphery of which is contiguous to said anvil and the outer portion of which has rolling supports, means for imparting to said table a rotary horizontal
- 45 movement about said pivot, and a flanging-hammer coacting with said anvil.
4. In a machine for circularly flanging plate metal, the combination of an anvil, a pivoted blank-carrying table the periphery of which 50 is contiguous said anvil, and the outer portion of which has rolling supports, attached to said table, means for imparting to said table a rotary horizontal movement about said pivot, a flanging-hammer coacting with said
- 55 anvil, and a base for said anvil in which is located a rolling support for the outer portion of said table, whereby the outer portions of said blank-carrying table may be rotatively supported while under the weight of the blank
- 60 which is being circularly flanged as herein described.
5. In a machine for circularly flanging plate metal, the combination of an anvil, a pivoted blank-carrying table the periphery of which 65 is contiguous said anvil, and the outer portion of which has rolling supports, means for imparting to said table a rotary horizontal
- movement about said pivot, and a flanging-hammer coacting with said anvil, the said hammer and the said anvil being carried on 70 the same base.
6. In a machine for circularly flanging plate metal, the combination of a flanging-hammer, a removable anvil seated in the same base that carries the hammer, a pivoted blank- 75 carrying table the periphery of which is contiguous said anvil, means for imparting to said table a rotary horizontal movement about said pivot, substantially as and for the purposes above set forth.
7. In a machine for circularly flanging plate metal, the combination of an anvil, a pivoted blank-carrying table the periphery of which is contiguous said anvil, and which has a central longitudinal slot, a vertical pivot-shaft 80 which projects through said slot and on which the table rotates horizontally, a sliding carriage which supports said pivot-shaft and in which it is free to rotate, means for moving said carriage and pivot-shaft toward 85 and away from the anvil, means for imparting to said table a rotary horizontal movement around said pivot, and a flanging-hammer coacting with said anvil, substantially as and for the purposes above set forth.
- 95 8. In a machine for circularly flanging plate metal, the combination of an anvil, a pivoted blank-carrying table, the periphery of which is contiguous said anvil and which has a central longitudinal slot, a vertical pivot-shaft 100 which projects through said slot and on which the table rotates horizontally, the head of said pivot-shaft being rectangular and fitting in said slot, a sliding carriage which supports said pivot-shaft and in which it is free to rotate, means for rotating said pivot-shaft and 105 said table horizontally, tracks upon which said carriage is supported, means for sliding said carriage on said tracks toward and away from said anvil, and a flanging-hammer coacting with said anvil, substantially as and for the purposes above set forth.
- 110 9. In a machine for circularly flanging plate metal, the combination of an anvil, a pivoted blank-carrying table the periphery of which 115 is contiguous said anvil and which has a central longitudinal slot, a vertical pivot-shaft which projects through said slot and on which the table rotates horizontally, the head of said pivot being rectangular and fitting in said 120 slot, a sliding carriage which supports said pivot-shaft and in which the shaft is free to rotate, a toothed quadrant rigidly connected with said pivot-shaft, a worm meshing with the teeth of said quadrant, said worm having 125 bearings connected with said carriage, a shaft passing through the axis of said worm, means for imparting rotary motion to said shaft, tracks upon which said carriage is supported, means for sliding said carriage back and forth 130 on said tracks toward or away from said anvil, and a flanging-hammer coacting with said anvil, substantially as and for the purposes above set forth.

10. In a machine for circularly flanging plate metal, the combination of an anvil, a pivoted blank-carrying table, having a central longitudinal slot, a pivot-shaft C having 5 a head C', the carriage D, the quadrant M, the worm L, the shaft G⁵, and means for rotating the same, supporting-tracks for said carriage, means for moving said carriage back

and forth on said tracks, supporting-rollers, a supporting-table, and a flanging-hammer, 10 coacting with the anvil, substantially as and for the purposes above set forth.
